JOSEPH SHERMAN REED, OF WINNFIELD, LOUISIANA.

STEEL CROSS-TIE AND RAIL-CLAMP.

1,222,133.

Specification of Letters Patent. Patented Apr. 10, 1917.

Application filed January 18, 1917. Serial No. 143,089.

To all whom it may concern:

Be it known that I, JOSEPH SHERMAN REED, residing at Winnfield, in the parish of Winn, and State of Louisiana, have invented a new and useful Steel Cross-Tie and Rail-Clamp, of which the following is a specification.

My invention, which has reference to improvements in railway ties and rail clamps, more particularly seeks to provide an improved, simple, inexpensive and stable construction of steel cross tie and rail clamp, in which coöperating portions of the tie and the rail clamping means are particularly designed for effectively retaining the rails in place and in which the stress of the parts, under pressure of passing trains, is so distributed to the rail and the clamping portions that the rails are held from lateral hammering against the clamping elements and the latter so secured that the clamp securing members are relieved from shearing or torsional strain.

With other objects in view that will hereinafter appear, my invention is an improved metallic tie and rail clamp that embodies the peculiar features of construction and novel combination of the parts to be described, specifically pointed out in the claims and illustrated in the accompanying drawings, in which:

Figure 1 is a perspective view of a combined metallic rail tie and clamp embodying my invention.

Fig. 2 is a longitudinal section of one end of the tie, and illustrates the rail clamp device as operatively applied to the rail.

Fig. 3 is a longitudinal section of one end of the tie and the rail clamp device that operates with the said tie end, the said device being shown in a position for being removed from the rail and the tie.

Fig. 4 is a top plan view of one end of the tie, the clamp device being removed.

Fig. 5 is an inverted plan view of the same end of the tie.

Fig. 6 is an inverted plan view of the said end of the tie with the clamp device operatively applied thereto.

Fig. 7 is a perspective view of one of the rail clamp devices, and

Fig. 8 is a cross section of the rail clamp device and the tie taken on the line 8—8 on Fig. 3.

In carrying out my invention, I provide a metallic tie, the main or body portion of

which is of the general inverted U-shape form in cross section having integral clamping members 2—2 for engaging the inner tread flanges 3—3 of the opposite rails 60 30—30, as shown.

At each end, the tie has a longitudinally elongated cavity or seat 4, the bottom 40 of which terminates with an inwardly and downwardly inclined aperture 5 that merges 65 with a longitudinally extended undercut seat or cavity 6 on the under side of the tie and which extends inwardly from the aperture 5, the reason for which will presently appear.

The lower side edges 10 of the tie 1 and 70 the closure plate 13 have interlocking dovetails and apertures, as shown.

The clamp members 7, the peculiar construction of which and their cooperative connection with the specially constructed seats 75 and apertures formed in the tie, as before referred to, include a clamping head 70 having the usual clamping jaw 71 for fitting over the outside flange of the base of the rail.

Head 70 also includes a pendent body portion 80 72 that is adapted, when the parts are operatively assembled, for freely fitting into the seat 4 in the upper face of the tie, as is best shown in Fig. 2, by reference to which it will be seen that the said body portion, 85 formed with a transverse aperture 73, has sufficient longitudinal play in the seat 4 so that when the clamp is forced back to its limit or operative position, that is, when the rail 30 is placed in position, the rear edge 90 72^a of the body portion 72, engages the end wall 40 of the seat 4 and with the base portion 75 of the head lapped over the sides and rear upper edges of the said seat 4, thereby forming, as it were, together with the rail 95 4, a perfect top closure for the said seat 4.

The body of the clamp 7 has a horizontal tread portion 76 which is flush with the top of the tie when the parts are assembled so as to be engaged by the rail and from the said tread portion, the body of the clamp merges into a downwardly inclined member 77 that passes through the inclined aperture in the tie and ends in a forwardly extended horizontal member 78 which fits into the undercut seat on the under side of the tie, as shown.

Each end of the tie 1 is transversely apertured as at 15 to receive a locking bolt 9 that passes through the said aperture 15 and the 110 aperture in the body portion of the clamp 72, when the parts are assembled as is best

shown in Figs. 2 and 8, the usual clamp nut 90 being provided for engagement with the bolt 9.

From the foregoing taken in connection with the drawings, the complete construction, the manner in which the parts are operatively applied and the advantages thereof will be readily apparent to those skilled in the art to which my invention relates.

- 10 It will be noticed, by referring particularly to Fig. 2, that the reason of forming the two longitudinally alined seats in the upper and lower sides of the tie top, joining the sides by an inclined aperture, and providing a clamping member having the peculiar shape stated, that when applied, the clamp, while effectively serving to hold the respective base flanges of the rail down to the tie, the said clamp is so positioned upon 15 the tie that the lateral stress from the rail is transmitted through the clamp directly against the tie, since the outer end of the clamp body engages the end wall of the seat 4 and thereby relieves the lock bolt 25 from transverse stress.

Further, by forming the inner end of the clamp, as shown and described, the said end is caused to snugly fit the seat on the under side of the tie and form a bottom closure 30 for the aperture through which the front end of the clamp is entered when adjusted for use.

By reason of forming the clamp and the tie portion engaged thereby as stated, a rail 35 fastener of a very simple construction is provided, that is highly efficient in its operation and extremely strong and durable.

The rails may be quickly fastened upon the ties and, when necessary, the clamps can 40 be almost instantly removed, since by removing the connecting bolts 9 and tilting the clamp to the position indicated in Fig. 3, the same can be readily pulled up (see arrow) and out of engagement with the tie.

45 What I claim is:

1. In a combined rail tie and rail clamping means, the combination with a hollow metallic tie having a pair of opposing integral clamping members adapted for receiving the adjacent inner base flanges of a pair of rails, each of the ends of the tie having a longitudinally extended upper and a longitudinally extended lower seat portion, the upper and lower seat portions being in longitudinal alinement, and an aperture in the tie body connecting the said seat portions; of a clamp device including a head portion having a member for clamping over the outer base flange of the rail, a body portion for fitting into the upper seat in the tie and in endwise abutment with the end wall of the said upper seat, said body including a

tread portion adapted for being engaged by the rail base and an extension adapted for being slipped through the aperture in the tie that connects the upper and lower seats and with the outer end thereof adapted for resting up in the undercut seat when the parts are at their operative position.

2. In a combined rail tie and rail clamp- 70 ing means, the combination with a hollow metallic tie having a pair of opposing integral clamping members adapted for receiving the adjacent inner base flanges of a pair of rails, each of the ends of the tie hav- 75 ing a longitudinally extended upper and a longitudinally extended lower seat portion, the upper and lower seat portions being in longitudinal alinement, and an aperture in the tie body connecting the said seat por- 80 tions; of a clamp device including a head portion having a member for clamping over the outer base flange of the rail, a body portion for fitting into the upper seat in the tie and in endwise abutment with the end wall 85 of the said upper seat, said body includ- 90 ing a tread portion adapted for being engaged by a rail base and an extension adapted for being slipped through the aperture in the tie that connects the upper and lower 95 seats and with the outer end thereof adapted for resting up in the undercut seat when the parts are at their operative position, the said body portion and the corresponding op- 100 posite walls of the sides of the upper seat portion having alining cross apertures and a bolt and nut connection for coöperating with the said apertured portions of the seat and the body of the tie as set forth.

3. A combined metallic railway tie and 100 rail clamp comprising a hollow body hav- 105 ing a pair of oppositely disposed integral rail clamps for engaging the inner adjacent flanges of the opposite rails, the outer ends of the tie each having an elongated seat in the top and a similar seat in the bottom, the two seats being in longitudinal alinement and a diagonally projected aperture that connects the top and bottom seats, a clamp having a jaw for fitting over the outer base 110 flange of the rail, and a body portion adapt- 115 ed for seating in the top seat of the rail, said clamp also including an inclined member adapted for projecting through the inclined aperture in the tie and a forwardly extend- 120 ed end for fitting into the seat in the under side of the tie and means for holding the clamp positioned in the said upper and lower seats and in the inclined aperture.

JOSEPH SHERMAN ^{his} X REED.
